(57) **CLAIM**

The ornamental design for a quadcopter frame, as shown and described.

DESCRIPTION

FIG. 1 is a perspective view of a quadcopter frame.
FIG. 2 is a front elevational view of the quadcopter frame of FIG. 1.

FIG. 3 is a rear elevational view of the quadcopter frame of FIG. 1.

FIG. 4 is a left side elevational view of the quadcopter frame of FIG. 1.

FIG. 5 is a right side elevational view of the quadcopter frame of FIG. 1.

FIG. 6 is a top plan view of the quadcopter frame of FIG. 1; and,

FIG. 7 is a bottom plan view of the quadcopter frame of FIG. 1.

The broken line showing of portions of the quadcopter frame depicts environment and forms no part of the claim.
